US0D1057565S

(12) **United States Design Patent** (10) **Patent No.:** **US D1,057,565 S**
(45) **Date of Patent:** **** Jan. 14, 2025**

(54) **PACKAGING BOTTLE**

(71) Applicant: **Shenzhen Zhongshun Trading Co., Ltd.**, Shenzhen (CN)

(72) Inventor: **Shuoqi Wu**, Chaozhou (CN)

(73) Assignee: **Shenzhen Zhongshun Trading Co., Ltd.**, Shenzhen (CN)

(**) Term: **15 Years**

(21) Appl. No.: **29/961,483**

(22) Filed: **Sep. 5, 2024**

(51) **LOC (15) Cl.** **09-01**

(52) **U.S. Cl.**

USPC **D9/560**; D9/743

(57) **CLAIM**

The ornamental design for a packaging bottle, as shown and described.

DESCRIPTION

FIG. 1 is a top, front, right side perspective view of a packaging bottle showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another top, front, right side perspective view of the packaging bottle shown in a separated state; and,

FIG. 10 is an enlarged view of portion 10 in FIG. 1.

The dash-dot-dash broken lines define the boundary of an enlarged view and form no part of the claimed design.

1 Claim, 10 Drawing Sheets
